TYPEWRITER MULTIPLE CASE SHIFT
MECHANISMRichard W. Sears, II, Evanston, Ill., assignor to
Woodstock Typewriter Company, Woodstock,
Ill., a corporation of Illinois

Application March 15, 1946, Serial No. 654,600

5 Claims. (Cl. 197—72)

1

This invention relates, in general, to typewriter machines, but more specifically to the provision of new and improved means whereby the use to which the machine may be put will be extended, by the provision of mechanism whereby the type bar segment may be shifted with respect to the platen, or the platen shifted with respect to the type bar segment.

Another important object is to provide improved means whereby the capacity or use to which the machine may be put may be extended.

A further object is to provide in a machine of this character, improved means for selectively shifting the type bar segment and the platen, one with relation to the other, according to the use to which the machine is to be put.

A further object is to provide improved means for maintaining the parts in their relatively positioned relation.

A still further object is to provide in a machine of this character, improved, simple, compact and efficient means for producing such results.

To the attainment of these ends, and the accomplishment of other new and useful objects as will appear, the invention consists in the features of novelty in substantially the construction, combination and arrangement of the several parts, hereinafter more fully described and claimed, and shown in the accompanying drawings exemplifying this invention, in which drawings

Fig. 1 is a detail fragmentary view showing the shift mechanisms or parts in elevation, and the manner in which they are arranged with respect to the type bar segment, type bar, and platen, and with the platen and type bar segment in lowered positions.

Fig. 2 is a detail fragmentary end elevation, parts being in section, of the key mechanism for raising the platen, and the means for holding it in raised position.

Fig. 3 is a fragmentary elevational view, parts being in section, of the type bar segment in raised position with respect to the platen, and the platen in lowered position.

Fig. 4 is a view similar to Fig. 3, showing the platen lowered and the type bar segment in a raised position.

Fig. 5 is a view similar to Fig. 3, showing both the platen and the type bar segment in raised position.

Fig. 6 is a view similar to Fig. 5, showing the platen raised and the type bar segment lowered.

Fig. 7 is a detail view of the locking mechanism shown in Fig. 1, and with the locking mechanism in an unlocked or releasing position.

2

In the co-pending application of James F. Koca, Serial No. 574,568, filed January 25, 1945, there is disclosed a typewriter machine of a similar construction, in which there is provided a type bar segment that is shiftable with respect to the platen, which latter is non-shiftable vertically, whereby the type bar segment may be adjusted and maintained in adjusted position, thereby adapting the machine for writing with the lower case or smaller type, or the upper case or larger type or capitals.

The present invention not only includes these features, but is also adapted to write with or employ two additional series of types, so that four sets or series of types are used. One of the types or characters of each of the four series is arranged on each of the type bars, and means are provided for selectively positioning the type bar segment and the platen, one with respect to the other, whereby the type of the desired series may be employed.

Means are provided for locking the parts in operative position, and means are also provided whereby the locking means may be readily rendered inactive, so that the parts may be shifted to the desired relative positions to reproduce the type or characters of the selected series.

Such an arrangement is desirable, as it sometimes happens that it is desired to use the machine for writing in different languages, which can be readily accomplished with the present invention, thereby imparting to the machine a larger scope of use, and, at the same time, providing a machine which is of a comparatively simple construction, and efficient and effective in operation, the transfer or conversion of its use from one language to the other being readily and quickly accomplished by the use of very little but effective mechanism.

In the present exemplification of this invention, the machine consists essentially of a frame-work 15, a shiftable type bar segment 16, having type carrying bars 17 pivotally mounted thereupon, as at 18, and which type carrying bar segment is shiftable from normal position for printing the lower case letters 19 on the type bar, to a lower position for printing the capital or upper case letters 20 on the bar.

As shown, the mechanism for shifting the type bar segment 16 embodies a shift key 21, embodying a lever 22, which is pivotally mounted, as at 23, upon a suitable part of the supporting frame of the machine. A link 24 is pivotally connected, as at 25, to an arm or extension 26 of the lever 22 (Fig. 1). The other end of the link 24 is pivot-

ally connected, as at 26^a, to a bell crank lever 27, which latter is pivotally mounted, as at 28, on a part of the sub-frame of the machine. The forward end 29 of the bell crank lever 27 is pivotally connected, as at 30, to an arm or extension 31 of the type bar segment 16, so that by operating the shift key 21, the type bar segment 16 will be raised or lowered, the segment being provided with suitable means (not shown) to guide it in its movements.

The type bar segment 16 is normally held in its upper position in any suitable manner, such as by means of a spring 32, one end of which is connected, as at 33, to the segment 16, and the other end is connected, as at 34, to the portion 29 of the bell crank lever 27. When the shift key 21 is depressed, the type bar segment 16 will be lowered against the stress of the spring 32, by the rotative movement of the bell crank lever 27—29. Upon releasing the shift key 21, the spring 32 will act to return these parts to normal positions, and the segment 16 will move into its upward or raised position, as shown in Fig. 1.

To maintain the parts in their normal operative position (as shown in Fig. 1), any suitable locking means may be provided, such as the locking means disclosed in the aforesaid application, which embodies a pair of links 33 pivotally connected, as at 34, to the bell crank lever 27, and to a bell crank lever 35, the latter being pivotally mounted, as at 36, on a part of the machine frame. The lever 35 is provided with a stop 37, which co-operates with a stop 40 on the arm of the bell crank lever 27.

A projection 38 on the link 24 is adapted to engage an arm of the lever 35 to render the locking means inactive, upon movement of the link 24 by the shift key 21, against the stress of the springs 41—42, all as disclosed in detail in the aforesaid co-pending application. Key levers 43, having operating keys 44, are removably and pivotally mounted, as at 45 (Fig. 1).

A bell crank lever 46 pivotally mounted, as at 47, is also pivotally connected with the lever 43, preferably by means of a pin and slot connection 48—49. A link 50 is pivotally connected at one end, as at 51, to the lever 46, and at its other end, as at 52, to an arm or portion 53, pivoted to the type bar segment 16. Another link 54 is pivotally connected, as at 55, to the arm 53, and, as at 56, to the type bar 17, so that when the key 44 is depressed, the type carrying portion of the lower case of letters on the type bar will strike the platen. When the shift key 21 is depressed, the letters in the upper case, or capitals, will strike the platen by the same operation of the type key 44.

Each of the type carrying bars 17 is provided with four letters or characters, two of such characters 57—58 being in addition to the series 19—20. The four characters are arranged in vertical alinement, and all of the characters on each bar are adapted to strike the platen by the operation of the same key 44. However, to accomplish this end, the type bar segment 16, and the platen 59, are adapted to be shifted and positioned, one with relation to the other, to render the respective series of characters active.

Each series of type embodies a horizontal line of characters, two of such series constituting an upper and lower case, either one of which is adapted to be positioned to strike the platen when positioned by the shift key 21; that is, whenever the type bar segment 16 or the platen 59 is relatively shifted. Furthermore, either set 75

or group of two lines or series of type is adapted to be rendered active or inactive, at will. That is, the machine may be set to selectively position either series in active or inactive position with respect to the platen, or vice versa. To that end, the machine carriage 60 (Fig. 1) is mounted in any well-known manner, to slide upon the frame 15, preferably through the medium of ball bearings 61, and the movement of the carriage is effected by the well-known spacer mechanism (not shown).

A platen supporting frame 62 is pivotally mounted upon brackets 63 on the carriage, by means of spaced arms 64—65, which are in turn pivoted to the carriage, as at 66—68, one pair of these arms being arranged at each end of the platen 59. The arms 64 are pivotally connected to the brackets, as at 66, and to the frame 62, as at 67. The arms 65 are pivotally connected, as at 68, by one end to the bracket 63, and at their other end, as at 69, to the frame 62. The arms are so arranged with respect to each other as to provide the proper raising and lowering movement of the platen. A spring 70 is provided to assist in raising the platen.

The raising movement of the platen 59 may be effected in any suitable manner, but preferably by means of a key 71 (Fig. 2), which is arranged in any convenient position in the key board, and the arm 72 of which is pivotally supported, as at 73, upon the machine frame. This arm 72 is provided with an extension 74, the end 75 of which engages a rocker or bell crank member 76, that is pivotally mounted, as at 77, upon a suitable portion of the machine frame. The end 75 of the extension 74 contacts the member 76 at 78, on one side of the pivot 77, and the arm or end 79 of the member 76 supports a track 80, preferably a rod or bar that extends across the machine frame parallel with, and spaced below the carriage 60 and platen 59.

The platen carrying frame 62 is supported by links 64—65 at both ends thereof. Secured to the frame in any suitable manner, as at 81, preferably by a pivotal connection, is a depending member 82, which terminates adjacent the track 80, and mounted upon the member 82, so as to run upon the track 80, is a roller 83, so as not to interfere with the spacing movement of the carriage and platen in either of their positions; that is, whether the platen is disposed in an elevated or a lowered operative position.

When the key 71 is depressed, the bell crank member 76 will be rocked, the track 80 will be elevated, and the frame 62 will also be elevated as the arms or links 64—65 will be swung about their pivots 66—68, and these links are so arranged as to maintain a parallel movement of the platen. Any suitable means may be employed to maintain the platen in either its raised or lowered position. A suitable and efficient means embodies a lever 84, pivotally mounted, as at 85, upon one of the brackets 63 of the carriage 60, and which is provided with open recesses or notches 86 which are adapted to receive a pin or projection 87 on the platen supporting frame 62.

Thus, when the lever 84 is swung in a direction to release the platen frame, the latter may be raised by depressing the key 71; or, if the platen is raised, it may be lowered by releasing the platen frame. The lever 84 is then swung in the opposite direction, so that one of the recesses or notches 86 will receive the pin or projection 87, and these parts will be locked in position.

In Figs. 5 and 6 of the drawings, the platen 59 is shown in both of its operative positions. That is, in Fig. 5 it is in a lowered position so that writing may be effected from the type comprising the series 19-20, while in Fig. 6 the platen is shown in a raised position to effect writing from the upper series of type 51-58. In either position, however, the shifting of the type bar segment 16 to enable the writer to employ the upper or lower case characters of either series, is accomplished by the same shifting mechanism; that is, by the operation of the shift key (Fig. 1), as the changing of the plane of operation of the platen does not in any way affect the operation of the shift mechanism.

With this improvement it will be manifest that two different groups of type or characters, each group embodying a plurality of series of type or characters, may be employed in the same machine, and that the operator, by simply operating a platen shifting key, can shift the platen in a direction transverse to its axis, to position the platen to be selectively rendered active or inactive with either of the groups of type or characters. The operation of all of the other parts of the machine will not be interfered with, and no other part of the machine will have to be adjusted or changed, to be able to write with either group of letters or characters. Furthermore, such change or shift may be readily made by any one, by shifting or operating the proper keys, without necessitating the services of an expert.

It is thought that the operation of this improved mechanism will be clearly understood from the foregoing description, but, briefly stated, it is as follows:

Assuming the parts to be in the position shown in Figs. 1 and 4, the platen 59 will be in its lowered position, so as to write with the series of letters or characters comprising the group 19-20, and the type bar segment 16 may be shifted by the key 21, to employ the upper case or series of letters 20, but before being shifted, the lower case, or series 19, will be in writing position with respect to the platen.

When, however, it is desired to write with the group of letters or characters 51-58, the platen 59 is shifted by operating the key 71, so as to swing the platen about the pivots 66-68, from the position shown in Fig. 1 to that shown in Figs. 5 and 6, the lever 84 being, of course, shifted to unlock or release the platen carrying frame 62 for such swinging operation. In either position of the platen, that is, in either the position shown in Fig. 1 or that shown in Figs. 5 and 6, the relative shifting of the type bar segment 16, or the operation of the keys of the key-board will not be interfered with.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. In a typewriter embodying type bars, each having two series of a plurality of characters, each series being individual to and active in one of the zones of operation into which the platen is moved, a platen carriage, a platen mounted upon the carriage for bodily swinging movement into two different zones of operation, a shift key for the platen carriage, a track located below and rearwardly of said platen, means mounting the track

for bodily shifting movement, means connected with the platen and movable along said track, means operated in response to the actuation of said key for shifting said track to shift the platen, whereby the zone of operation of said platen may be changed, and means located rearwardly of the platen for releasably locking said platen in each of its zones of operation.

10 2. In a typewriter embodying type bars, each having two series of a plurality of characters, each series being individual to and active in one of the zones of operation into which the platen is moved, a platen carriage, a platen mounted upon the carriage for bodily swinging movement into two different zones of operation, a shift key for the platen carriage, a track located below and rearwardly of said platen, means mounting the track for bodily shifting movement, means connected with the platen and movable along said track, means operated in response to the actuation of said key for shifting said track to shift the platen, whereby the zone of operation of said platen may be changed, a pivotally mounted lever located on said carriage rearwardly of said platen, and interengaging means between said lever and the platen carriage for locking the platen in its adjusted position with respect to the said carriage.

15 3. In a typewriter, a platen carriage, a platen support pivotally mounted upon the carriage, a platen carried by said support and movable with respect to the carriage into two different active zones, a track disposed below and fixed with respect to the typewriter frame, a depending member connected with said support and movable along said track as the said carriage is moved, a support for said track, key-actuated means for shifting said track, whereby the said platen support will be shifted to move the said support with respect to the carriage to position the platen in different zones for movement with the carriage, a lever connected with said carriage and located rearwardly of the platen and extending thereabove, and interengaging means between the lever and said support for locking the platen and the support in the position to which they have been adjusted with respect to the carriage.

20 4. A typewriter embodying a carriage, a platen support, links connecting the support to the carriage for bodily shifting movement with respect thereto, in directions transverse to the line of travel of the carriage, a platen carried by said support, an actuating key, means disposed between the key and said platen support for bodily shifting the support to move the platen into a different zone of operation, and means located rearwardly of the platen for locking the support and platen in their adjusted position with respect to the carriage, the platen being adapted to return to normal position with respect to the carriage when said locking means is rendered inactive.

25 5. A typewriter embodying a carriage, a platen support mounted thereupon for movement therewith and for bodily movement with respect thereto, a platen mounted upon the support, a member pivotally connected to the support and depending below the carriage, a track below the carriage, with which said member engages to move therewith, a bell crank lever, one arm of which supports said track, key means embodying an arm adapted to engage and swing said lever about its pivot to shift the track, and thereby move the platen support with respect to the carriage to position the platen in another operating zone, and locking means between the platen support and

said carriage including a pivotally mounted arm located rearwardly of the platen for releasably maintaining the platen in any position to which it has been adjusted with respect to the carriage.
